HOSPITAL SERVING TRAY

Herbert W. Peters, Milwaukee, Wis.

Application January 3, 1956, Serial No. 39,570

Term of patent 14 years

(Cl. D44—10)

Fig. 1 is a perspective view of a hospital serving tray showing my new design;

Fig. 2 is a top plan view thereof;

Fig. 3 is a front elevational view thereof;

Fig. 4 is a side elevational view thereof;

Fig. 5 is a sectional view thereof along the line 5—5 of Fig. 3; and

Fig. 6 is another sectional view thereof along the line 6—6 of Fig. 2.

I claim:

The ornamental design for a hospital serving tray, substantially as shown.
